CORPORATION, A CORPORATION OF MICHIGAN

GRINDER MACHINE

Application filed February 6, 1930. Serial No. 426,211.

Although the present invention is broadly entitled, its essential features are particularly pertinent to so-called "centreless" or "roll" grinding machines of that general type which has been described and claimed in my pending application, Serial No. 383,439, filed August 5th, 1929,—to which reference may be had for various advantageous features of general construction and mode of operation that need not be herein detailed.

The present organization resembles that referred to in its general purposes and also in providing for the rotation of a work unit, 15 such as a tappet valve that is to be ground, by a suitable engagement of a part thereof, such as the valve stem, by relatively moving rotation-imparting members,—these being disposed one within the other about axes which 20 are so related as to provide convergent peripheral surfaces, and an additional surface, preferably provided or carried by a so-called "steady rest", being employed to oppose the action of gravity upon the work unit; and 25 the main advance upon which protection is herein sought is such a relative disposition of the mentioned surfaces as to obviate any "jumping" or other vertical or peripheral displacement of the work unit.

30 More specifically, the present invention, in a preferred embodiment thereof, may involve not only a lateral offsetting, but a vertical offsetting of an axis of curvature and/or rotation of an inner rotation-imparting member (preferably in the form of a drum) relatively to the axis of the cooperating outer member,—the effect being that, in the immediate region of their contact with the valve stem (or a corresponding part of any work unit,—assumed to be substantially cylindrical, in case the rotation-imparting surfaces are cylindrical) any convergence of said surfaces is upward, rather than downward.

45 Other objects of the present invention (in connection with which it should be understood that either the operating and control devices of the mentioned application or any preferred operating and control device may be employed, and that the mentioned surfaces 50 may, if desired, serve for both a rotating and

a surface-perfecting effect) will be best understood from the following description of an illustrative embodiment of the invention, taken in connection with the appended claims and the accompanying drawings.

Fig. 1 is a front or end elevational view; and Fig. 2 is a small-scale plan view, diagrammatically showing the general relationship of the main parts herein described to a grinding wheel and its associated parts.

In general, the machine selected for description and shown in the drawings comprises a pair of cylinders or drums, differing in radius of curvature, both being arranged for rotation and the smaller drum being preferably designed to rotate within the larger end in a direction opposite to the direction of rotation of said larger drum. The internal surface of the larger drum may be provided with a friction element, such as a lining formed of a hard rubber composition; and the exterior surface of the smaller drum may be equipped with a grinding face (if a grinding operation is intended to be performed by its engagement with a work unit) or with merely a friction face similar to that provided within the outer drum. The cylinders are positioned with their surfaces in sufficiently close proximity to one another in

one region to enable both of them to contact with a part of a work unit, such as a valve stem. An additional member, providing a work support, may be interposed between the surfaces of the mentioned cylinders in the mentioned region, the contact of the oppositely rotating drums with the work unit being relied upon to cause the same to revolve about its own axis while contacting with a flat or rounded hard upper surface of said work support; and the machine may obviously be utilized merely to rotate the stem of the valve while the head is being ground, or it may be equipped, as above suggested, to grind the stem simultaneously with the head grinding operation,—the fixity of the axis of rotation of the work unit being important in either case and assured by the mentioned offsetting of the axis of curvature of the inner drum or its equivalent.

Referring to Fig. 1, a suitable base casting 100

10, remote from the observer, may be secured to the bed of any suitable supporting table or bench 5 and may provide a fore-and-aft aperture in which is suitably journaled a shaft 12. Keyed to and supported by an end of the shaft 12 is shown a small drum 15; and driving power may be applied directly or indirectly to some suitable part of the shaft 12. Assuming the axis of shaft 12 to be fixed, a 15 drum-supporting casting 20 may be provided with any desired lateral adjustment means, such as a tongue and groove connection, as suggested at 21, extending in a direction at right angles to the line of the shaft 12,—the 20 casting 20 having preferably the general form of a ring 22 supported upon a flat base. The internal periphery of the ring 22 of the casting 20 is provided with suitable bearing surfaces for a large drum 30. Fitted upon the 25 central part of the drum 30 and preferably between oppositely inclined bearing rings, not seen, is a gear 33; and secured to the upper portion of the ring 22 is a third casting 40, in which is journaled a shaft 41. This shaft 25 may carry both a remote sprocket gear 42, indirectly driving or driven from the shaft 12, and also a gear 43 shown as directly engaging the mentioned gear 33 upon drum 30,—the use of a sprocket chain for the former 30 purpose being suggested by dotted lines 45.

A friction lining 50 of hard rubber composition, or the like, to provide a rotation-imparting surface, is shown as secured to the inner periphery of the large drum 30 by means of a shouldered ring 51, a cooperating lining 60 being preferably provided upon the external periphery of the small drum 15 and secured thereon by means such as a shouldered ring 61. The linings 50 and 60 may be of like composition if it is desired only to rotate the valve stem rather than to grind it. If, however, it is desired to grind the stem or to polish it, one or both of the mentioned linings may naturally be formed from a material suitable to this purpose; and, in any case, some rotative effect may obviously be obtained even though only one of the mentioned drums, or equivalent members, be provided with a rotation-imparting surface and suitably advanced.

A work support may comprise an arcuate sheath for a part of the small drum 15, and also bored-out end portions such as that shown at 70, by which it may be supported,—the forward end portion being adapted to fit around a shouldered bushing 72 on the end of shaft 12 in front of drum 15, and means such as a washer 73 and a nut 74 being employed on the end of said shaft to secure said bushing, and thereby said work support, in place. The right edge 76 of the arcuate portion of the work-supporting member provides a surface interposed between the mentioned surfaces, upon which the stem of a 65 valve 100, or other work unit is supported,—

room for the head of the valve being provided by a cutting away of said sheath at 77. The forward end portion 70 is shown as provided with a spider portion or web 78, having an elongated slot 79 in the end thereof, to receive a bolt 80 secured in a bracket 81 upon the supporting bench 5,—a nut 82 being tightened against the spider 78 to secure the work supporting member in any adjusted position.

Any suitable mechanism may be employed to vary the distance between mentioned surfaces, as by resiliently advancing and/or manually shifting the large drum 30 relatively to the small drum 15 and the work support, to permit engagement and easy removal of work units of various diameters. For example, in the base of the casting 20, there may be secured a plurality of pins 120 which extend through the ends of an apertured bracket 123, secured to the bench 5; and compression springs 124 may be so positioned upon the said pins as to abut at one end against the bracket 123 and at the other end against nuts 125, adjustable upon the free ends of said pins. The springs 124 may be so tensioned by the nuts 125 as normally to maintain the large drum 30 in operative position relative to the work support and the small drum 15. Secured in the left side of the casting 20, in a bifurcate bracket 126, is shown a roller 127, positioned above and between pins 120. Secured to the bench 5 and between the pins 120 is a bearing member 130, in which is journaled a shaft 131. Secured to the shaft 131, to the right of the bearing 130, is a cam 132 with its face in operative contact with the roll 127; and secured to the cam 132 there is shown a lever 133, by which the cam may be manually rocked with the shaft 131 in the bearing 130 to force the casting 20, and therewith the drum 30, to the right in opposition to the pressure of springs 124; but it should be understood that all features above referred to, being among those described in the mentioned application, are herein set forth for the sake of clarity and completeness of description only; and also that the outer member, whether or not it has the form of a drum, may always have a greater radius of curvature than the inner member in the region of nearest approach between said members.

It will be observed that the described specific arrangement of the means for rotating the drum 30 will cause it to advance in a direction opposite to the rotation of the shaft 12 and the drum 15, and the gearing may be such that the small drum 15 rotates downwardly toward the work-supporting surface 76 at a greater speed than the outer drum 30 rotates upwardly in order to minimize any tendency for the work to leave the surface 76; and, in the present instance, the construction and arrangement of mentioned parts is 130

such that the axis of the drum 30 is disposed in a plane substantially below that of drum 15. At least one point in the axis of rotation of the work unit 100 thus preferably lies in a line common to an inclined radius of drum 15, if extended, and a horizontal radius of drum 30,—this novel construction having the notable advantage that a local substantial parallelism, or a slight upward convergence, of the cooperating rotation-imparting surfaces serves substantially to obviate risk of any "jumping" or "climbing" movement of the work during a grinding or other operation, so long as both the laterally disposed surfaces, shown as having unlike curvatures contact therewith.

This combination permits the grinding wheel 110 to be of an inexpensive type, and rotated by any preferred means; and, the general mode of operation of this machine having been indicated in connection with the foregoing description, it may be noted, in conclusion, that power can be applied to either shaft 12 or shaft 41, and that the use of the present innovations involves no complications in design, although the organization retains all advantages, such as accessibility of essential parts, ease of feed and rapidity of action, mentioned in the prior application referred to, while additionally insuring a steadier retention of the work units than was originally provided for.

All forms of the invention may involve the use of inner and outer drums, or equivalent members, respectively providing relatively movable lateral surfaces, at least one of said surfaces being of such material as to impart rotation to a work unit disposed therebetween, means for advancing at least one of said surfaces, an interposed member providing an additional unit-engaging surface between the mentioned surfaces, and means for so supporting said members as substantially to prevent disengagement of said unit from any of said surfaces during rotation thereof,—this being preferably accomplished by so disposing centres of curvature and/or rotation as to render cooperating surfaces upwardly convergent in the region of their engagement of said unit, the angles between lines of engagement of said surfaces with said unit being always less than 180°. In other words the line contacts between the unit and the drum 30, drum 60 and support 76 are on a greater than semi-cylindrical surface of the unit. Also the line contacts of the drums and unit are spaced less than 180 degrees about the upper surface of the unit.

It should, however, be understood that various features of the described organization might be independently used and that the unit to which rotation is imparted may have any desired general form or function, so long as an engaged part such as the men-

tioned stem, or its equivalent, is, or becomes, substantially circular in cross-section; and also that various special modifications and applications of the principles involved might easily be devised by workers skilled in the pertinent arts, if informed of the foregoing, all without departure from the scope of the present invention as the latter is indicated by the following claims:

1. In a work-rotating mechanism of the general character described: an inner member which provides a convex surface for the engagement of a unit to be rotated; an outer member whose inner surface has a radius of curvature which exceeds that of said convex surface,—at least one of said members having its surface formed of a material which adapts it to impart rotation to the mentioned unit; means for relatively advancing the last mentioned member; an interposed member providing an additional unit-engaging surface between the mentioned surfaces; and means for so supporting said members as substantially to prevent disengagement of said unit from any of said surfaces during rotation thereof.

2. In a work-rotating mechanism of the general character described: an inner member which provides a convex surface for the engagement of a unit to be rotated; an outer member whose inner surface has a radius of curvature which exceeds that of said convex surface,—at least one of said members having its surface formed of a material which adapts it to impart rotation to the mentioned unit; means for relatively advancing the last mentioned member; an interposed member providing an additional unit-engaging surface between the mentioned surfaces; and means for so supporting said members as substantially to prevent disengagement of said unit from any of said surfaces during rotation thereof,—the respective inner and outer members being drums whose axes are relatively offset in both a horizontal direction and a vertical direction.

3. In a work-rotating mechanism of the general character described: an inner member which provides a convex surface for the engagement of a unit to be rotated; an outer member whose inner surface has a radius of curvature which exceeds that of said convex surface,—at least one of said members having its surface formed of a material which adapts it to impart rotation to the mentioned unit; means for relatively advancing the last mentioned member; an interposed member providing an additional unit-engaging surface between the mentioned surfaces; and means for so supporting said members as substantially to prevent disengagement of said unit from any of said surfaces during rotation thereof,—the respective inner and outer members being drums whose axes are relatively offset in both a horizontal direction and a vertical direction.

vertical direction, said concave surface and said convex surface being upwardly convergent in the region of their engagement of said unit, and the mentioned surface of the interposed member being below said unit.

4. In a work-rotating mechanism of the general character described: an inner member which provides a convex surface for the engagement of a unit to be rotated; an outer member whose inner surface has a radius of curvature which exceeds that of said convex surface,—at least one of said members having its surface formed of a material which adapts it to impart rotation to the mentioned unit; means for relatively advancing the last mentioned member; an interposed member providing an additional unit-engaging surface between the mentioned surfaces; and means for so supporting said members as substantially to prevent disengagement of said unit from any of said surfaces during rotation thereof,—the respective inner and outer members being drums whose axes are relatively offset in both a horizontal direction and a vertical direction, and the lines of engagement of said surfaces with said unit being on a greater than semi-cylindrical surface of the unit.

5. In a machine of the class described, the combination of: a rotatable drum peripherally supported and having a rotation-imparting surface; a second drum also supported for rotation but eccentrically positioned within the mentioned drum; common driving means for said drums; and means for preventing peripheral displacement, in either direction, of a work unit interposed between said drums.

6. In means for rotating a work unit, a convex movable member, a concave movable member and a stationary member, respectively engaging said unit, said members engaging the unit at points located on a greater than semi-cylindrical surface of the unit.

45 7. In means for rotating a cylindrical work unit, a convex movable member, a concave movable member, and a stationary member, respectively engaging said unit, said members engaging the unit at points located on a greater than semi-cylindrical surface of the unit, at least one of the first mentioned members being provided with a surface when advanced toward the unit to impart rotation thereto, and means for moving said members toward or from each other.

8. In means for rotating a cylindrical work unit, a convex movable member, and a concave movable member respectively engaging said unit, the points of engagement of said members to said unit being located on a greater than semi-cylindrical surface of the unit, said members comprising drums whose axes are relatively offset both horizontally and vertically.

9. In combination, a rotatable drum, means

for rotating the drum, a second drum disposed within the first drum eccentrically thereof, a work support disposed between the outer surface of the inner drum and the inner surface of the outer drum, the support being so located that the adjacent surfaces of the drums extend upwardly beyond the sides of the work support in only converging relation.

10. In combination a rotatable drum, means for rotating the drum, a second drum disposed within the first drum eccentrically thereof, a work support disposed between the outer surface of the inner drum and the inner surface of the outer drum, the support being so located that the adjacent surfaces of the drums are adapted to contact with a cylindrical unit supported on the work support at points spaced less than 180° around the surface of the work piece opposite the support.

11. In combination a rotatable drum, means for rotating the drum, a second drum disposed adjacent the first drum, a work support disposed between adjacent peripheral surfaces of the drums, the arrangement being such that a cylindrical work piece supported on the support engages the latter and the surfaces of the drums located on a greater than semi-cylindrical surface of the work piece.
